UNITED STATES PATENT OFFICE.

GEORGE C. CUMMINGS, OF WESTERN SPRINGS, ILLINOIS.

TELEPHONY.

997,756.

Specification of Letters Patent. Patented July 11, 1911.

Application filed October 14, 1909. Serial No. 522,588.

To all whom it may concern:

Be it known that I, GEORGE C. CUMMINGS, citizen of Canada, subject of King Edward VII of Great Britain, residing at 5 Western Springs, in the county of Cook and State of Illinois, have invented a certain new and useful Improvement in Telephony, of which the following is a full, clear, concise, and exact description, reference being 10 had to the accompanying drawings, forming a part of this specification.

My invention relates to telephony, and has for its object the provision of an improved system that is especially adapted to the telephonic connection of substations with a central office and in which the apparatus and circuit arrangements are simplified and at the same time well adapted to the various operations of the system. 15

20 The system of my invention is well adapted to that class of service in which the substations may call the central office, and the central office may call the substations, but in which the substations may not call each 25 other.

The accompanying drawing illustrates one practical embodiment of my invention, the line and substation apparatus and the central station apparatus being diagrammatically shown. 30

In the system illustrated I have shown but three telephone lines extending from substations A B C to the central office D, but it is to be understood that I do not limit 35 myself to the number of such lines. The telephone lines are preferably metallic, one side of each preferably terminating at the corresponding substation in a pair of multiply related contacts *b*, *c*, while the companion side terminates in a switch spring *a*. The normal contact *b* is connected with its 40 side of the telephone line through a condenser *d*, and the alternate contact *c* is connected with said side of the telephone line 45 through the corresponding substation transmitting telephone *e*. The position of the spring *a* is governed by the switch hook *f* in such a manner that when said switch hook occupies the position to which it is 50 brought when supporting the telephone receiver *g*, the switch *a* engages its normal contact *b*, and when said switch hook is relieved of the weight of the receiver said switch *a* engages its alternate contact *c*. 55 Each telephone line terminates at the central office in a pair of switches or key

springs *h* which have normal contacts that are connected with switches or key springs *i*. The normal contacts of the springs *i* constitute the terminals of circuit connections 60 that include a battery *k* that is common to all of the lines and line magnets or relays *l* that are individual to the lines. Though the battery *k* is thus normally connected with all of the lines, the flow of current therefrom over the telephone lines is normally prevented by the condensers *d* that are normally in serial relation with the sides of their associate lines by way of the normal contacts *b* that are engaged with the 65 switches *a* when said switches are moved by the associate switch hooks when supporting telephone receivers. When a party at a telephone substation desires to communicate with the central office, such party removes 70 his telephone receiver *g* from its switch hook *f*, thereby to exclude the associate condenser *d* from circuit and to include the telephone transmitter *e* in circuit, said transmitter being included in a metallically 75 continuous conductor that metallically unites the two sides of the calling telephone line, thereby to afford a closed circuit for the battery *k* and the line magnet *l* of the calling line. This magnet is consequently energized 80 thereby occasioning the presentation of a line signal. In the preferred embodiment 85 of the invention the magnet *l* does not directly present the line signal, but is used merely as a relay to close a local signaling 90 circuit including a line signal lamp *m*, the battery *k* and an armature switch *n*, the signal thereby occasioned being a visual signal. I also provide means for creating an audible signal, which means is desirably common 95 to all of the lines and is desirably brought into operation by any actuated relay *l*. The said means desirably resides in an electromagnet *o* that opens and closes the conductor *p* that includes it in circuit, this conductor being connected at one end with one 100 side of the battery *k*, and having connection at its other end with the multiply connected contacts *q* provided for the switches *r* that are connected with the other side of 105 the battery *k* and which are governed by the relays *l*. When, therefore, any line is calling, the visual signal at *m* is accompanied by an audible signal produced at the common source *o*, the magnet *o* operating as a 110 buzzer. If the attendant at the central station fails to notice the visual calling signal

displayed by the line lamp *m* belonging to a calling substation, the audible signal should attract his attention.

The attendant at the central station will, 5 in response to the line signal, move the key lever *s* belonging to the terminals *h* of the calling line to a position where such terminals will be separated from their normal contacts, thereby to exclude the signaling apparatus *l, m, o*, from association with the calling line, the line terminals *h* consequently engaging their alternate contacts that constitute terminals of a conducting element that includes the telephone outfit *t*, belonging 10 to the central station, and the common battery, the terminals *h* of the calling line thus being connected with each other through said telephone apparatus *t* and the common battery *k*, said common battery 15 thereby supplying the central station and the calling substation transmitters with operating current.

If the central station attendant desires to signal a substation, key lever *s* belonging to 20 a selected line is thrown to that position in which a source of signaling current is connected in circuit with the called line. In the embodiment of the invention illustrated, the alternate contacts of the key springs *i* 25 constitute the terminals of a secondary or induced coil *u*, which is looped in the called line when said springs *i* engage their said alternate contacts. The primary or inducing coil *v* is at this time included serially 30 in circuit with the circuit making and breaking armature switch of the magnet *o* and the winding of said magnet, this circuit being traceable from the battery *k* through the magnet *o* and its said armature switch, the 35 primary or inducing winding *v*, the alternate contact of the left hand key spring *i* individual to the called line, the contact *w* then engaged by said alternate contact, thence back to said battery. As a consequence 40 of the closure of the circuit just traced, current through the inducing or primary coil is rapidly interrupted, whereby a suitable signaling current is impressed upon the secondary or induced coil *u* that will 45 operate the signal receiver at the selected station. When the called station responds, the operator at the central station will 50 throw the actuated key lever *s* to its extreme position so as to establish telephonic connection 55 between the telephones at the central and called stations in the manner which has been described.

When it is desired to place two subscribers in telephonic connection one of the keys *s*, 60 say the key corresponding to the calling station, occupies normal position and the other key (the one corresponding to the called station) is moved to wedge its springs *i* into connection with their alternate contacts. The two lines are then connected by

way of the springs *h* of the first key and their normal contacts, the springs *i* of said key and their normal contacts, the alternate contacts of the springs *i* of the second switch and the springs *h* of the second switch together with their normal contacts. 70

An important feature of my present invention resides in the elimination of the commonly employed signal receiver and providing such a circuit relation and equipment in the common battery system, that the telephone receivers *g* at a called station may also constitute a signal receiver. This feature of my invention is realized by causing the telephone receiver *g* to be connected with the sides of their associated telephone lines through their associate condensers *d* when said receivers are upon their switch hooks, said condensers normally preventing the flow of battery current over the lines, while permitting the passage of wave form signaling current from some suitable source, as the secondary *u*, over any line called, and through the telephone receiver *g* of the called line whose diaphragm is thereupon vibrated with sufficient rapidity by the wave form signaling current as to cause an audible signal. When any substation desires to signal the central station, the telephone transmitter *e* at the calling station is substituted for the condenser thereat in the manner and with the results that have been specified. 80

While I have herein shown and particularly described the preferred embodiment of my invention, I do not wish to be limited to the precise details of construction and circuit arrangement illustrated, but 90

Having thus described my invention, I claim as new and desire to secure by Letters Patent the following: 100

1. A telephone system including a plurality of telephone lines extending from substations to a central office, telephone receivers, telephone transmitters, switch hooks and condensers at the substations, switching devices at the substations operated by the switch hooks when moved by the telephone receivers when placed thereon to cut the condensers into serial relation with the telephone receivers and the telephone lines, and serving to include the telephone transmitters in serial relation with the sides of the telephone lines and telephone receivers to the exclusion of the condensers when the telephone receivers are removed from their switch hooks, whereby direct current may flow through the telephone receivers and transmitters, line signal devices at the central office individual to said telephone lines, a source of direct current, said line signal devices and source of direct current being normally connected with the telephone lines to enable the closure of their circuits when the telephone receivers are removed from 110

- their switch hooks, means at the central office for impressing signaling current upon the telephone lines that is adapted to find passage through the condensers and which 5 is capable of operating the telephone receivers at the substations as signal receivers, and switching devices at the central office that are individual to the telephone lines for including the telephone transmitter at 10 the central office in circuit with said source of direct current and serving when thus operated to exclude the line signal devices from operative relation with the lines.
2. A telephone system including a plurality of telephone lines extending from substations to a central office, signal receivers at the substations, an induced or secondary winding at the central office, an inducing winding at the central office, a circuit making and breaking magnet for interrupting current flowing through the inducing winding, switching mechanism at the central office for bringing said induced winding into operative relation with a line to be called and 20 the signal receiver at the substation thereof, and for closing circuit through said magnet and the inducing winding, and line signal 25

devices individual to the telephone lines, said magnet being common to said lines and also serving as a common line signal. 30

3. A telephone system including a plurality of telephone lines extending from substations to a central office, signal receivers at the substations, an induced or secondary winding at the central office, an inducing 35 winding at the central office, a circuit making and breaking magnet for interrupting current flowing through the inducing winding, switching mechanism at the central office for bringing said induced winding into 40 operative relation with a line to be called and the signal receiver at the substation thereof and for closing circuit through said magnet and the inducing winding, and means whereby a substation calling party may operate said magnet as a line signal. 45

In witness whereof, I hereunto subscribe my name this 12th day of October A. D., 1909.

GEORGE C. CUMMINGS.
